UNITED STATES PATENT OFFICE.

CHARLES W. CHENEY, OF BOSTON, MASSACHUSETTS.

MASSAGE APPARATUS.

Application filed June 15, 1923. Serial No. 645,564.

To all whom it may concern:

Be it known that I, CHARLES W. CHENEY, a citizen of the United States of America, and resident of Boston, in the county of 5 Suffolk and State of Massachusetts, have invented new and useful Improvements in Massage Apparatus, of which the following is a specification.

This invention relates to a massage appliance of the general type illustrated in 10 U. S. Patent No. 1,339,299; an object of the present invention being the provision of a construction which will facilitate electro-therapeutic massage treatments and minimize the energy expended in giving the 15 proper treatment.

Certain embodiments of the appliance are shown in the accompanying drawings, in which:—

20 Fig. 1 is a side elevation of the massage appliance;

Fig. 2 is a plan view with parts removed as on the line 2—2 of Fig. 1;

Fig. 3 is a bottom plan view;

25 Fig. 4 is a section on the line 4—4 of Fig. 1;

Fig. 5 is a fragmentary section on the line 5—5 of Fig. 3;

Fig. 6 is a partial end elevation;

30 Fig. 7 is a section on the line 7—7 of Fig. 6;

Fig. 8 is a bottom plan of a modified form of massage members; and

Fig. 9 is a section on the line 9—9 of 35 Fig. 8.

In the particular embodiment here illustrated the appliance is shown as including a frame or casing A having controlling handles B and C and a rotor shaft D carrying 40 the massage head E.

The massage head is provided with suitable massaging members for mechanical kneading or massage of the flesh of a patient, these members being of any desired 45 form or shape, characteristic forms such as the balls particularly illustrated in Fig. 5 and the frusto-conical rollers of Figs. 8 and 9 being shown. The operation of the rotor D serves to impart a spinning movement to 50 the head E carrying the massaging members about in a circular path over the patient while the position of the device as an entirety is controlled by the handles B and C so that its effect may be localized or extended over a considerable area. Suitable 55 electrical connections are provided between

the massaging members and a source of electrical energy so that the flesh engaging and kneading parts will carry an electrical current to the portion of the body of the patient engaged thereby, the current being 60 grounded through the patient who therefore receives the combined benefits of simultaneous massage and electro-therapeutic treatment.

Control means are preferably provided for the flow of therapeutic current and also for the rotor current (not shown) so that the massaging device may be employed without electrical connection or the electrical 70 current may be supplied to the massaging members during manual manipulation thereof without actuation of the rotor.

In the specific embodiments illustrated, the handle C has extending through it a 75 suitably driven flexible shaft member 10 for operating the worm shaft 11 which is journaled in casing A. Worm 12 on shaft 11, by engagement with pinion 13, drives the rotor shaft D which projects from the casing A. This rotor shaft has a socket 14 receiving the non-conducting bushing 15 and cap 16 which together with washer 17 serve to insulate the tip 18 from the rotor shaft D. This tip has a socket 19 detachably receiving the threaded stud 20 of the base 80 plate 21 forming a part of the massage head E.

Base plate 21 has secured thereto discs 22 having annular flanged portions 23 intermediately located on the faces of the discs and forming interior races for the anti-friction balls 24. Sleeves 25 have a driven fit with the exterior of the flanges and their inturned edge portions 26 serve to retain 85 the massage members 27 seated against the thrust bearings 24 for free rotation.

An alternative construction of massage head is shown in Figs. 8 and 9, and comprises a base plate 28 having the attaching stud 29 and spaced annular flanges 30 and 31 connected by angularly disposed pintles 32. In this form frusto-conical rollers 33 carried by the pintles provide the flesh engaging massaging members, their frusto-conical form allowing the rollers to move freely over the flesh on rotation of the head without any pulling or twisting action.

In the use of the invention the shaft 10 is suitably actuated, spinning the rotor and 110 massaging head which is moved over the body of the patient by handles B and C.

- The massaging members 27 or 33 thus spin in a small area whose location is varied as desired by shifting the device as an entirety.
- 5 To permit electro-therapeutic treatment during the massage a contact brush 34 rides against the member 18, this brush being supported in the non-conducting socket 35 of brush arm 36 which depends from casing 10 A adjacent rotor shaft D. A connecting wire 37 extends through arm 36 from casing 34' of spring-pressed brush 34 to one terminal of switch member 38. The other terminal 39 has a wire leading to a suitable source 15 of electrical energy, the terminals being operatively connected as by the switch arm 40.

When the switch is closed current will flow from the source of electrical energy through wire 37, brush 34 and part 18 to the 20 massaging head. The head and massaging members are of conducting material, and the current for the electro-therapeutic portion of the treatment will flow through said members to the exact portion of the body 25 which is the subject of the treatment at that particular moment.

I claim:

1. A device for use in electro-therapeutic 30 massage treatments comprising a frame, a rotary head carried by the frame, means insulating the head from the frame, and means on the frame in non-conducting relation thereto for supplying an electric current to the head.
- 35 2. A device for use in electro-therapeutic massage treatments comprising a frame, a rotary head carried by the frame, means insulating the head from the frame, means on the frame in non-conducting relation thereto for supplying an electric current to the head, and additional means carried by the 40 frame for rotating the head.
3. A massage appliance comprising a frame, a rotor in the frame, means for actu-

ating the rotor, an insulated massage head 45 carried by the rotor, said head having massaging members of electrically conductive material, and a brush arm carried by the frame having a brush in operative relation to the head for supplying an electric current to the conductive massage members.

4. An electro-therapeutic massaging device comprising a frame, a rotor journaled in the frame and a massage head carried by the rotor in insulated relation thereto, 50 massaging members carried by the head, said head and members being formed of electrically conductive material, and means on the frame engaging the head for supplying electric current to the massage members by way of the head.

5. A device of the character described including a frame, a rotor journaled in the frame having a terminal portion insulated 55 from the frame and body of the rotor, means for actuating the rotor, a brush arm carried by the frame and extending adjacent the rotor, a conductor within the brush arm, and a contact brush in circuit with the conductor, said brush engaging the insulated 60 terminal portion of the rotor.

6. A device of the character described including a frame, a rotor journaled in the frame having a terminal portion insulated 65 from the frame and body of the rotor, means for actuating the rotor, a brush arm carried by the frame and extending adjacent the rotor, a conductor within the brush arm, a contact brush in circuit with the conductor, 70 said brush engaging the insulated terminal portion of the rotor, and a massage head carried by said terminal portion of the rotor, said head having flesh massaging members electrically connected with the energized terminal of the rotor.

Signed by me at Boston, Mass., this 12th day of June, 1923.

CHARLES W. CHENEY.
